(57) **CLAIM**

The ornamental design for a motorcycle fork as shown and described.

DESCRIPTION

FIG. 1 is a top, front and left side perspective view of a motorcycle fork showing our new design;

FIG. 2 is a bottom, front and right side perspective view thereof;

FIG. 3 is a top, rear and left side perspective view thereof;

FIG. 4 is a bottom, rear and right side perspective view thereof;

FIG. 5 is a front elevational view thereof;

FIG. 6 is a rear elevational view thereof;

FIG. 7 is a left side view thereof;

FIG. 8 is a right side view thereof;

FIG. 9 is a top plan view thereof;

FIG. 10 is a bottom plan view thereof;

FIG. 11 is an enlarged view of portion 11 in FIG. 1;

FIG. 12 is an enlarged view of portion 12 in FIG. 1; and,

FIG. 13 is an enlarged view of portion 13 in FIG. 2.

The evenly broken lines in the drawings illustrate portions of the motorcycle fork which form no part of the claimed design.

The unevenly dashed broken lines in FIGS. 1-2 and 11-13 indicate the boundaries of the enlarged views and are used for annotative purposes only. They do not limit or define the scope of the claimed design.
